UNITED STATES PATENT OFFICE.

JOHN E. PFEFFER, OF MINNEAPOLIS, MINNESOTA, ASSIGNOR TO CONTINENTAL ENGINEERING CO., OF CHICAGO, ILLINOIS, A CORPORATION OF MAINE.

AUTOCYCLE.

1,132,380.

Specification of Letters Patent. Patented Mar. 16, 1915.

Application filed October 17, 1913. Serial No. 795,711.

To all whom it may concern:

Be it known that I, JOHN E. PFEFFER, a citizen of the United States, residing at Minneapolis, in the county of Hennepin and 5 State of Minnesota, have invented certain new and useful Improvements in Autocycles; and I do hereby declare the following to be a full, clear, and exact description of the invention, such as will enable others 10 skilled in the art to which it appertains to make and use the same.

My invention relates to automobiles, but is particularly directed to the improvement of the construction and arrangement of the 15 running gear and body of so-called autocycles. These so-called auto-cycles are, as is well known, really small automobiles, usually of narrow gage, but having four wheels and adapted to carry one or two 20 persons.

Generally stated, the invention consists of the novel devices and combinations of devices hereinafter described and defined in the claims.

25 As one highly important feature of my present invention, I make the side bars of the running gear frame hollow or tubular and utilize the same as casings to inclose the driving chains, or belts that transmit the 30 power from the engine driven shaft to the rear traction wheels. These tubular side bars are preferably made dust and oil tight, so that they will exclude dust and hold oil.

With this improved arrangement, I 35 preferably employ a conventional differential gear and a divided jack shaft, the sections of which are connected at their adjacent ends, in the usual way, to the driven wheels of the differential gear; but in this improved 40 arrangement, the outer ends of this jack shaft are extended through suitable bearings on the tubular side bars into the interiors thereof, and are provided with driving sprockets located within and incased by 45 said side bars. At their rear ends, the tubular side bars are pivoted on or around the rear axle, and this rear axle is a divided axle, the sections of which are connected 50 to the respective rear traction wheel. By this arrangement, the front portion of the running gear frame is rendered capable of vertical movements without changing the distance between the driving and driven 55 sprockets. The front portion of the running gear frame is spring-supported on the front

axle, which front axle is provided with the usual pivoted trunnions on which the front wheels are journaled. The engine is preferably carried on the front portion of the running gear frame, and hence, is spring- 60 supported.

So far as my present invention is concerned, various different, but suitable connections may be made between the engine crank shaft and the differential gear; but, 65 preferably, I employ a frictional transmission mechanism disclosed and broadly claimed in my companion application filed of even date herewith. A suitable engine incasing hood, or housing, is applied on the 70 front portion of the running gear frame.

The vehicle body is fulcrumed, or pivotally connected at its front end to the forward portion of the running gear frame at a point, preferably, approximately alined with 75 the rear portion of the engine frame; and the rear portion of said body is spring-supported on the rear portion of the running gear frame. In this way, the vehicle body is spring-supported both at front and rear, 80 and, at the same time, while the engine is also spring-supported, the running gear frame has a vertical movement which is very different from that of the engine, and the effect of the vibrations of the engine on the 85 body is reduced to a minimum.

In the accompanying drawings which illustrate the invention, like characters indicate like parts throughout the several views.

Referring to the drawings: Figure 1 is a 90 view in side elevation with some parts broken away and some parts sectioned, illustrating my invention as applied to a small automobile or so-called auto-cycle; Fig. 2 is a plan view of the running gear of the 95 auto-cycle, some parts being broken away and some parts being sectioned, and Fig. 3 is a section taken approximately on the line $x^3 x^3$ on Fig. 2.

The running gear frame is made up of a 100 pair of long parallel tubular side bars 1 and suitable cross connections, such as cross bars 3, 4, and 5, and a tubular rear axle casing 6, which parts are rigidly connected. The tubular side bars 1 are preferably rectangular in cross section. Rigidly secured to the rear end portions of the tubular side bars 1, in axial line with the rear axle casing 6, are rear axle bearings 7, that extend outwardly 105 from the said bars. The rear axle 8 is cen- 110

trally divided and is journaled in the bearings 7, and in the casing 6, and the rear sprockets 9, which are located within the said tubular bars, are secured to the respective sections of the said divided rear axle. The rear traction wheels 10 are secured to the outer ends of the sections of the said divided rear axle.

The engine, which, as illustrated, is a multi-cylinder explosive engine 11, is shown as secured to the front cross bars 5 of the running gear frame, and a face friction wheel 12 is secured to the rear end of the crank shaft of this engine. This face friction wheel 12 is one of the elements of the frictional transmission mechanism disclosed in my said co-pending application, and for the purposes of this case, it is only necessary to note that the same co-operates with a peripheral friction wheel 13 mounted to rotate with, but to slide laterally upon a drum 14, which drum, through a suitable differential gear incased therein, drives the sections of a centrally divided so-called jack shaft 15. The ends of this jack shaft 15 are journaled in suitable bearings on the side bars 1 and extend into the interior of the said side bars, and are there provided with driving sprockets 16. Link belts or sprocket chains 17 that are entirely incased by the side bars 1, run over the sprockets 16 and over the rear sprockets 9 on the divided rear axle. The rear ends of the tubular bars are closed, and the front ends thereof, are also preferably closed, but preferably also, just in front of the driving sprockets 16, the tubular side bars 1 are provided with plugs or partitions 18 which shorten up the chambers 1^a in which the chains 17 and sprockets 9 and 16 are located. These chambers 1^a are adapted to contain oil so that the said sprockets and chain may be run in oil, and at the same time are, of course, incased so that dust, dirt, rain and the other elements, are excluded therefrom.

The spring connection between the front ends of the side bars 1 and the front axle 19 is, as shown, afforded by half elliptical springs 20, rigidly secured to the central portions of the said front axle, pivotally connected at their front ends to the front ends of said bars, and at their rear ends, connected to said bars by short links 21. The front wheels 22 of the running gear are pivoted to the usual trunnions 23 which, in turn, are pivotally connected to the ends of the front axle and are provided with arms 24 connected for parallel movements by a cross link 25. The steering connections for oscillating the link 25 to control the steering movement of the front wheels may be of the usual or any suitable construction. The engine hood 26, as already stated, is secured to the front portion of the running gear frame. The vehicle body 27, which, as shown, is pro-

vided with two seats 28, located, one ahead of the other, is, at its front portion, shown as provided with fulcrum lugs 29, pivotally connected at 30 to the side bars 1, at points approximately in line with the rear edge of the hood 26.

The numeral 31 indicates the usual steering wheel forming part of a suitable steering mechanism not illustrated in full. As a simple and efficient way of spring-supporting the rear end of the body 27 from the rear end of the side bars 1, leaf springs 32 are employed, and these springs, at their front ends, are attached to the sides of the body 1, preferably by pivot bolts 33. The free rear ends of the springs 32 rest on bearings afforded by outwardly projecting studs or lugs 34 on the rear ends of the frame bars 1. At points just over the intermediate portions of the springs 32, the body 27 is provided with longitudinally adjustable bearings 35 that rest directly on said springs. By longitudinal adjustments of the bearings 35 in a forward direction, the resilience of the spring may be increased, and, obviously, a rearward adjustment will accomplish the reverse result.

The construction above described, while extremely simple and of small cost, is strong, durable and generally efficient. The driving mechanism is not only incased out of contact with the dust, elements, and run in oil, also these parts are kept out of sight and guarded so that they cannot catch the clothes or any other article. The manner of supporting the body makes the vehicle easy riding.

What I claim is:

1. In an automobile running gear, the combination with front and rear wheels, of hollow side bars pivotally supported at the axis of the rear wheels and spring-supported at their front ends, of a transmission mechanism including driving and driven wheels and co-operating belts located within said side frames.

2. In an automobile running gear, the combination with front and rear axles and front and rear wheels, of hollow side bars pivotally supported on said rear axle and spring-supported at their front ends, an engine driven counter shaft extended into the front ends of said hollow side bars, and a transmission mechanism including driving and driven wheels, respectively, on said counter shaft and rear axle, located within said hollow side bars and secured, respectively, on said counter shaft and rear axle, and belts also located within said hollow side bars and running over co-operating driving and driven wheels running over the alined driving and driven wheels.

3. In an automobile running gear, the combination with front and rear wheels and front and rear axles, the latter being a

- divided axle, of hollow dust-tight side bars pivoted on said rear axle and spring-supported at their front ends, an engine driven counter shaft extended into the front portions 5 of said hollow side bar, driving and driven sprockets located within said side bars and secured, respectively, on said counter shaft and rear axle, and sprocket chains also located within said side bars and 10 arranged to run over alined driving and driven sprockets.
4. In an automobile running gear, the combination with the front and rear wheels, of hollow side bars pivotally supported at 15 the axes of the rear wheels, and spring-supported from the front wheels, of a transmission mechanism including driving and driven wheels and coöperating belts located within said side frames.
- 20 5. In an automobile running gear, the combination with front wheels, rear wheels, front axle and rear axle, the latter being a divided axle, of dust-tight tubular side bars pivotally mounted on said rear axle and 25 springs supported on said front axle, an engine carried on the front portions of said side bars, a transverse divided jack shaft extended into said side frames provided with driving sprockets within said side 30 frames, driven sprockets secured to said divided rear axle within said side frames, sprocket chains running over said driving
- and driven sprockets within said side frames, and an engine-driven differential gear connecting the sections of said jack 35 shaft.
6. In an automobile, the combination with hollow side bars pivotally supported on the rear axle and spring-supported from the front axle, of a vehicle body fulcrumed at 40 its front end on the forward portions of said side bars and spring-supported at its rear end on the rear portions of said side bars, and driving wheels and belts located in said hollow side bars. 45
7. In an automobile, the combination with a running gear frame including hollow side bars pivotally supported on the rear axle and spring-supported on the front axle, of a vehicle body fulcrumed on its front end on 50 the front portion of said running gear frame and spring-supported at its rear end of the rear portions thereof, and an engine mounted on the spring supported front end of said running gear frame and having connections located in said hollow side bars for 55 driving the rear wheels.

In testimony whereof I affix my signature in presence of two witnesses.

JOHN E. PFEFFER.
